UNITED STATES PATENT OFFICE.

ALLEN KANDER, OF PHILADELPHIA, PENNSYLVANIA, ASSIGNOR TO THE WHIKOU CORPORATION, A CORPORATION OF DELAWARE.

DESIGN FOR A COMBINED LAMP SHADE AND BOX OR SIMILAR ARTICLE.

Application filed April 5, 1924. Serial No. 9,186. Term of patent 7 years.

To all whom it may concern:

Be it known that I, ALLEN KANDER, a citizen of the United States, residing at 218 East Sedgwick Street, Philadelphia, in the county of Philadelphia and State of Pennsylvania, have invented a new, original, and ornamental Design for a Combined Lamp Shade and Box or Similar Article, of which the following is a specification, reference being had to the accompanying drawing, forming a part thereof.

Fig. 1 is a view in elevation of the invention; and Fig. 2 is a top view of the same.

I claim:

The ornamental design for a combined lamp shade and box or similar article, substantially as shown.

ALLEN KANDER.
